[57] CLAIM

The ornamental design for an expandable support pedestal for a camera, as shown and described.

DESCRIPTION

FIG. 1 is a perspective view of the expandable support pedestal for a camera showing my new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof; and,

FIG. 8 is a perspective view thereof with the expandable support pedestal for a camera in a collapsed position.
